UNITED STATES PATENT OFFICE.

CHARLES R. NELSON, OF CHICAGO, ILLINOIS, ASSIGNOR TO SIEBER & TRUSSELL MANUFACTURING COMPANY, A CORPORATION OF MISSOURI.

FILE-BINDER.

No. 813,817.

Specification of Letters Patent.

Patented Feb. 27, 1906.

Application filed August 1, 1903. Serial No. 167,922.

To all whom it may concern:

Be it known that I, CHARLES R. NELSON, a citizen of the United States, and a resident of Chicago, county of Cook, and State of Illinois, have invented certain new and useful Improvements in File-Binders, of which the following is a specification and which are illustrated in the accompanying drawings, forming a part thereof.

This invention relates to permanent binders for loose leaves of that type in which a pair of vertical posts are set in a base-plate, the sheets or leaves to be bound being apertured to engage the posts and a pressure and binding plate being applied above the sheets and locked to the posts.

The invention consists in novel means for locking the pressure and binding plate to the vertical posts, as hereinafter described, and as illustrated in the accompanying drawings, in which—

Figure 1 is a detail perspective of the device, the cover-plate for the locking mechanism being removed. Fig. 2 is a plan view of the binding device not in use. Fig. 3 is a plan view of the same with the cap-plate removed. Fig. 4 is a longitudinal central section on the line 4-4 of Fig. 2, the parts being shown in the position in which they are represented in Fig. 3. Fig. 5 is a detail end elevation. Fig. 6 is a perspective of the key used for controlling the locking mechanism, and Fig. 7 shows a modified form of the binding-plate.

The base-plate 10 is shown as being in the form of a strip, preferably of metal, of a length as great as or greater than the width of the sheets X to be secured. A pair of vertical posts 11 12 are rigidly fixed to the plate 10. A binding-plate 13, apertured to receive the posts 11 and 12 and to run loosely thereupon, is of substantially the same form as the plate 10. A binding-plate 14 rests upon the plate 13 and is in sliding engagement therewith, being secured by means of a T-stud 15, the shank of which projects through an elongated aperture in the plate 14. This latter plate is apertured, as shown at 22 24, to receive the posts 11 and 12, the centers of the apertures, however, being slightly closer together than the centers of the posts. The plate 14 is controlled by a screw-bolt 16, in threaded engagement with the block 17, fixed

to the plate 13, the bolt having its outer end squared, as shown at 18, for the engagement of a socketed key 19 and being in swiveled engagement with an upturned flange 20 of the plate 14. This binding-plate is split at its opposite end, as shown at 21, through to the aperture 22 and is preferably recessed at 23 23, opposite its opposite sides, as shown at 23 23, opposite such aperture, so that as the plate is drawn by the screw 16 until the side wall of the aperture 22 engages the post 11 the two end pieces, separated by the split 21, are forced apart, closing together, however, by reason of the resiliency of the metal upon the movement of the plate in the opposite direction.

The aperture 24 is so disposed relatively to the aperture 22 that its side wall does not engage the post 12 until after the engagement of the side wall of the aperture 22 with the post 11 and the split end of the plate has been widened as described. By this means the plate 14 is caused to bite into both posts, even though the latter may be somewhat out of true either because of defective construction or because they have become bent in use.

In actual practice devices of this kind may be subjected to rather severe usage, and the posts, not being stayed, are liable to be bent, rendering the locking device inoperative or inefficient. This difficulty is entirely avoided by the construction shown and described.

The binding-plate may be split longitudinally a short distance from both of its apertures, as shown at 26 and 27 in Fig. 7, thereby rendering it laterally expandible by contact with both posts and increasing the available range of movement. This construction, however, I do not claim specifically in this application, as I have more fully described and claimed the same in a copending application, Serial No. 248,124, which is a division of this one.

At 25 is shown a cover-plate for inclosing the locking mechanism, such plate being apertured to accommodate the posts 11 and 12.

I claim as my invention—

1. In a loose-leaf binder, in combination, a base-plate, a pair of posts set therein, a pressure-plate running on the posts, a binding-plate apertured to fit upon the posts and being in slidable engagement with the pressure-plate, the distance between one of the apertures and the remoter side of the other aper-

ture differing from the distance between the posts correspondingly measured the binding-plate being elastic at one of its apertures.

2. In a loose-leaf binder, in combination, a base-plate, a plurality of posts rising therefrom, a pressure-plate running on the posts, a binding-plate in sliding engagement with the pressure-plate and apertured to fit loosely on the posts and being expansible at one of its apertures and non-expansible at the other aperture, and means for shifting the binding-plate laterally as to the posts.

3. In a loose-leaf binder, in combination, a base-plate, a plurality of posts rising therefrom, a pressure-plate running on the posts, a binding-plate in sliding engagement with the pressure-plate and having an aperture for loosely receiving each post and being expansible at one of its apertures and non-expansible at the other aperture, a block secured to the pressure-plate and having a threaded aperture, and a screw engaging such aperture and in swiveled engagement with the binding-plate.

25 4. In a loose-leaf binder, in combination, a

base-plate, a pair of posts rising therefrom, an apertured pressure-plate running on the posts, a binding-plate slidingly engaging the pressure-plate and apertured to fit loosely on the posts, the centers of its apertures being closer together than the centers of the posts, such last-named plate being split from one end to the adjacent aperture, and means for sliding such plate laterally as to the posts.

5. In a loose-leaf binder, in combination, a base-plate, a pair of posts set therein, a pressure-plate running on the posts, a binding-plate apertured to fit upon the posts and being in slidable engagement with the pressure-plate, one of the apertures in the binding-plate being of less width at one end than the diameter of the post with which it co-operates and the plate being resiliently expansible at such aperture, and means for adjustably shifting the binding-plate in one direction to engage it with both posts.

CHARLES R. NELSON.
